Primary Examiner — Marissa J. Cash(74) *Attorney, Agent, or Firm* — Seed Intellectual Property Law Group LLP(57) **CLAIM**

The ornamental design for a airship-airplane hybrid vehicle as shown and described.

DESCRIPTION

FIG. 1 is an axonometric lower right front view of airship-airplane hybrid vehicle showing my new design.

FIG. 2 is an axonometric upper left rear view of the airship-airplane hybrid vehicle of FIG. 1.

FIG. 3 is a front view thereof.

FIG. 4 is a rear view thereof.

FIG. 5 is a left side view thereof.

FIG. 6 is a right side view thereof.

FIG. 7 is a top plan view thereof; and,

FIG. 8 is a bottom plan view thereof.

The broken lines in the figures depict portions of the airship-airplane hybrid vehicle that form no part of the claimed design.

1 Claim, 7 Drawing Sheets(56)
